WORK GUIDE FOR SEWING MACHINES

Julius Rosenzweig, New York, N. Y.

Application June 6, 1942, Serial No. 446,002

6 Claims. (Cl. 112—144)

This invention relates to work guide for sewing machines. It is particularly directed to an adjustable guide adapted to be attached to the work plate of a sewing machine to guide bands, ribbons or other work during the sewing operation, when making tucks and for the like purposes.

In making tucks, the material is folded and stitched longitudinally close to the fold. Difficulty has been found in guiding the folded material so that the stitching can be made close to the fold. An object of the present invention is therefore to provide a guide of the character described having improved means for guiding the folded material in such a manner as to permit stitching very close to the folded edge thereof, whereby to facilitate the making of tucks in the material.

A further object of this invention is to provide a guide of the character described which is adjustable for bands of various widths.

Another object of the present invention is to provide a guide of the character described, formed with an upwardly extending fin or projection adapted to engage one edge of the material to be sewed, said fin or projection being so constructed that it may be received within the slot of the presser foot, said guide being adjustable on the work plate of the sewing machine to also permit engagement of said fin or projection with an outer side of the presser foot or beneath the upturned toe portion of the presser foot.

Still another object of this invention is to provide a guide of the character described having an adjustable work engaging member which may be fixed to the guide in various adjusted positions to accommodate bands or work of different width, said guide being so constructed that the adjustable member may be moved out of the way when not in use, the guide furthermore being formed with a fixed work engaging member to be used for guiding work of predetermined width, when the adjustable guide is not in use.

Yet another object of this invention is to provide a guide of the character described, which may be attached to the work plate in various adjusted positions.

A still further object of this invention is to provide a strong and durable guide of the character described, which shall be relatively inexpensive to manufacture, easy to assemble, adjust and manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

10 Fig. 1 is a top plan view of a work plate and presser foot with a guide embodying the invention mounted on the work plate and showing the adjustable member in inoperative position in dot, dash lines;

15 Fig. 2 is a front elevational view of the structure shown in Fig. 1;

Fig. 3 is a cross-sectional view taken on line 3—3 of Fig. 1;

20 Fig. 4 is a partial top plan view taken below the presser foot and illustrating the method of guiding the material along the guide fin during the sewing operation;

Fig. 5 is a cross-sectional view taken on line 5—5 of Fig. 1; and

25 Fig. 6 is a cross-sectional view taken on line 6—6 of Fig. 1.

Referring now in detail to the drawing, 10 designates the work plate of a sewing machine, and 11 designates a presser foot of usual construction used therewith, while numeral 12 designates an improved work guide 12 embodying the invention.

The work plate 10 is formed with a pair of parallel, longitudinal slots or openings 14 and 15, in which are located the oscillating feeders 14a and 15a respectively.

As shown in the drawing, slot 14 is longer than slot 15. The work plate is also formed with an opening 17, aligned with slot 15 and located in front thereof. Said slot 17 has an offset portion 18 extending toward slot 14 and through which the needle 20 passes during the sewing operation.

45 The presser foot 11 is formed with a longitudinal slot 22 and has portions 23 and 24 on opposite sides of said slot. Portion 23 is in alignment with the feed member 14a, whereas presser foot portion 24 is in alignment with the feed member 15a. As shown in the drawing, the needle 20 passes through the slot 22 in the presser foot. The front ends of the toes of presser foot portions 23, 24 are inclined upwardly and forwardly.

55 The work plate 10, the presser foot 11, the feeds

14a and 15a and the needle 20 as described above are of usual and well known construction.

The guide 12 embodying the invention comprises a member 30 generally in a direction inclined rearwardly and to the right relative to front edge of the work plate 10, as shown in Fig. 1. Said member 30 comprises a flat, L-shaped portion 31 lying on the work plate 10, and having a longitudinal portion 31a and a portion 31b extending forwardly from the right end of portion 31a. Extending from portion 31b is an integral, horizontal guide rail arm 32 offset upwardly from said flat portion 31, and connected to said portion 31b, by a shoulder 33. Arm 32 is parallel to portion 31a and spaced therefrom by slot 40 15 and extends therebeyond to the left.

Portion 31 has at the rear of its left end, an edge or shoulder 35, perpendicular to the front edge of work plate 10 and adapted to contact one side of the presser foot 11. Said portion 31a is furthermore formed with a portion 36 disposed forwardly of shoulder 35 and extending beyond said shoulder. Extending upwardly from said portion 36, is a fin or fixed guide stop or projection 37 parallel to said shoulder 35.

The projection 37 thus likewise extends in a direction at right angles to the front edge of the work plate 10, and is adapted to be received within slot 22 to contact the inner edge of presser foot portion 24. Thus, the distance between the projection 37 and shoulder 35 is substantially equivalent to the width of the presser foot portion 24. Projection 37 has an upwardly and forwardly inclined upper edge 37a of substantially the same inclination as the toe portions of the presser foot, for the purpose hereinafter appearing.

Arm 32 is also flat and disposed in a horizontal plane somewhat above the plane of the top surface of the work plate 10. The outer end of arm 31 is bent upwardly and backwardly, as at 41, to form a fixed guide stop 42 when guiding a work of a predetermined width, which width is equivalent to a distance between the projection 37 and the stop 42, in a direction parallel to the front edge of the work plate.

Slidably mounted on arm 32 is a movable and adjustable guide stop 45. The guide stop 45 has a sleeve 46 slidably receiving the arm 32. On arm sleeve 46 is an adjustable screw 47 to fix said adjustable stop in any desired adjustable position. Extending from sleeve 46 is an upwardly turned guide member 48, parallel to the projection 37. Arm 32 may be marked with a scale 50 which is calibrated to give the normal width of the work guided between the projection 37 and the adjustable guide stop 45.

It will be noted that the work is engaged at one edge by the projection 37 and at the other edge by the guide stop 45. The guides for the opposite edges of the work are thus not aligned with each other, so that the work is guided at different longitudinal points at opposite edges thereof, thus facilitating guiding of the material during the sewing operation.

If it is desired not to use the adjustable guide 45, screw 47 may be loosened and member 45 then moved to the dotted line position shown in Fig. 1, within slot 40, so as to be out of the way.

The work plate 10 is formed with a pair of 70 tapped holes 56 and 57, either one of which can receive a screw 58 with a wide head. Portion 31 of member 30 is formed with a pair of parallel, longitudinal slots 59, 60. The screw passes through one of the slots and is screwed into one 75

of said tapped openings. Upon turning the screw, the head thereof will press the guide plate firmly against the work plate 10 to hold it against movement.

It will be noted that the guide member 12 can be adjusted, by loosening the screw 58, to bring the projection 37 either within the slot 22 as shown in full lines in Fig. 1, or against the outer side of the presser foot as shown in dotted lines in Fig. 1, or beneath the toe of the presser foot, as is also shown in dotted lines in said Fig. 1, or to other positions.

When the projection 37 is within the slot 32, the work may be stitched very close to its edge, since there is very little distance between the plane of the projection 37 and a plane parallel thereto and passing through the needle 20. Thus, with a guide embodying the invention, tucks may be made by folding a piece of material longitudinally and then stitching the folded piece with the folded edge contacting the projection 37 during the stitching operation, thus making a line of stitching close to the fold. When the material is unfolded, a fine tuck will be produced. The improved guide member 12 may be used for guiding ribbons, hat bands, or any other similar work during the stitching operation. If desired, the guide 37 alone may be used.

It will now be understood that the positions of the guides for the opposite edges of the work may be adjusted relative to the line of stitching.

If desired, the turned back portion 42, 41 may be omitted.

The advantages of constructing the guide to lie at an inclination to the presser foot is that the rail arm projecting forwardly and to the left, is out of the way of the presser foot. Furthermore, the projection 37 may be easily adjusted by moving the guide about the attached screw 58. Thus, the projection 37 may be moved forwardly of the presser foot so as to be out of the way of said foot. Such adjustment would not be readily accomplished if the guide were at right angles to the presser foot. Furthermore with such construction, the projection 37 can be placed close to the needle so as to aid in producing a fine tuck.

In making bands for the crowns of uniform caps, such as policemen or firemen caps, or the like, it is necessary to make a tuck above the lower edge of the band. Heretofore, it was necessary to mark a line on the band where the tuck was to be made in order to have the tuck at a particular height above the lower edge of the band. With the improved guide herein disclosed, it is possible to make such a tuck without necessity for marking the band before the stitching operation. The reason is that the improved guide can be adjusted to the desired width of the band and the guide will then guide the band through the sewing operation so as not to vary the line of stitching relative to the edges of the band.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A guide of the character described, compris-

ing a member formed with a slot to receive a screw for attaching the guide to the work plate of a sewing machine, said member being formed with a shoulder adapted to contact the outer side of a presser foot, and being formed with an upwardly projecting fin parallel to said shoulder and spaced therefrom and adapted to be received within the slot of the presser foot, said member being furthermore formed with an arm, an adjustable stop member slidably mounted thereon, and means to fix the adjustable stop member on said arm in various adjusted positions.

2. A work guide for a sewing machine comprising a member having a flat portion adapted to contact the top of the work plate of the sewing machine, and an arm parallel to said flat portion, said member being formed with a slot between said arm and said flat portion, said arm extending beyond said flat portion, said arm being formed at its outer end with a fixed stop, said flat portion being formed with an upwardly projecting portion adapted to engage within the slot of a presser foot, said flat portion being formed with a slot to receive means for fastening said member to the work plate of the sewing machine, said flat portion being furthermore formed with a shoulder parallel to said projection and adapted to engage the presser foot, and adjustable guide means on said arm adapted to be moved into the slot in said member.

3. A sewing machine guide comprising a member having a flat L-shaped portion comprising a longitudinal arm, and an arm extending at right angles thereto, a rail arm extending from the second arm of said L-shaped portion and disposed parallel to the longitudinal arm of said L-shaped portion and separated therefrom by a slot and extending in the same direction as said longitudinal arm, and therebeyond, said L-shaped portion being formed with a longitudinal slot to receive means for fastening said guide member to the work plate of a sewing machine, said longitudinal arm being formed with an upwardly extending projection adapted to engage one longitudinal edge of a piece of cloth to guide said piece during the sewing operation, and a member slidably mounted on said rail arm for engaging the opposite edge of said piece of cloth during the stitching operation, said slidably mounted member being movable into the slot which separates the rail arm from said longitudinal arm, so as to be out of the way when not in use, said longitudinal arm having a shoulder adapted to engage one side of the presser foot, said shoulder being parallel to said projection and spaced therefrom.

4. A sewing machine guide comprising a member having a flat L-shaped portion comprising a longitudinal arm, and an arm extending at right angles thereto, a rail arm extending from the second arm of said L-shaped portion and disposed parallel to the longitudinal arm of said L-shaped portion and separated therefrom by a

slot and extending in the same direction as said longitudinal arm, and therebeyond, said L-shaped portion being formed with a longitudinal slot to receive means for fastening said guide member to

5 the work plate of a sewing machine, said longitudinal arm being formed with an upwardly extending projection adapted to engage one longitudinal edge of a piece of cloth to guide said piece during the sewing operation, a member slidably mounted on said rail arm for engaging the opposite edge of said piece of cloth during the stitching operation, said slidably mounted member being movable into the slot which separates the rail arm from said longitudinal arm so as to be out of the way when not in use, and a fixed stop at the outer end of said rail arm adapted to engage an edge of the piece of cloth being stitched when said slidably mounted member is moved to inoperative position, and to prevent said slidably mounted member from coming off said rail arm.

20 5. A guide of the character described, comprising a member formed with a slot to receive a screw for attaching the guide to the work plate of a sewing machine, said member being formed with a shoulder adapted to contact the outer side of a presser foot, and being formed with an upwardly projecting fin parallel to said shoulder and spaced therefrom and adapted to be received within the slot of the presser foot, said member being furthermore formed with an arm, an adjustable stop member slidably mounted thereon, means to fix the adjustable stop member on said arm in various adjusted positions, said stop being parallel to said fin, and said arm being inclined to said fin and stop.

25 6. A sewing machine guide comprising a member having a flat L-shaped portion comprising a longitudinal arm, and an arm extending at right angles thereto, a rail arm extending from the second arm of said L-shaped portion and disposed parallel to the longitudinal arm of said L-shaped portion and separated therefrom by a slot and extending in the same direction as said longitudinal arm, and therebeyond, said L-shaped portion being formed with a longitudinal slot to receive means for fastening said guide member to the work plate of a sewing machine, said longitudinal arm being formed with an upwardly extending projection adapted to engage one longitudinal edge of a piece of cloth to guide said piece during the sewing operation, and a member slidably mounted on said rail arm for engaging the opposite edge of said piece of cloth during the stitching operation, said slidably mounted member being movable into the slot which separates the rail arm from said longitudinal arm, so as to be out of the way when not in use, said longitudinal arm having a shoulder adapted to engage one side of the presser foot, said shoulder being parallel to said projection and spaced therefrom, said rail arm being inclined to said projection.

JULIUS ROSENZWEIG.
